UNITED STATES PATENT OFFICE.

LOUIS ANDERSON, OF CHICAGO, ILLINOIS.

GRAIN-SHOCKER.

1,146,838.

Specification of Letters Patent. Patented July 20, 1915.

Application filed January 13, 1913. Serial No. 741,811.

To all whom it may concern:

Be it known that I, LOUIS ANDERSON, a citizen of the United States, and resident of Chicago, county of Cook, and State of Illinois, have invented certain new and useful Improvements in Grain-Shockers, of which the following is a specification, and which are illustrated in the accompanying drawings, forming a part thereof.

- 10 The invention relates to grain shockers, and more particularly to those designed to be used in conjunction with machines for reaping grain and binding it into bundles, the grain shucker then serving to receive 15 the completed bundles of grain and to deposit them upon the ground in the form of a shock when a sufficient number of the bundles for that purpose have been produced.
- 20 The object of the invention is to provide a grain shucker of the type described which shall be efficient and reliable in operation, and of such construction as to permit of its being applied as an attachment to machines 25 for reaping and binding grain now in use.

In the accompanying drawings—Figure 1 is a plan view showing a shock former embodying the features of improvement provided by the invention and details of a reaping and binding machine; Fig. 2 is a rear elevation of the same, some of the parts of the reaping and binding machine being shown in cross section; Fig. 3 is a plan sectional view taken on the line 3—3 of Fig. 2; Figs. 4 and 5 are vertical sectional views taken on the lines 4—4 and 5—5, respectively, of Fig. 3; Fig. 6 is a detail sectional view taken on the broken line 6—6 of Fig. 1; Fig. 7 is a detail plan view, some of the 40 flooring parts of the harvesting machine being removed and certain details of the mechanism being shown in section; Fig. 8 is a detail sectional view taken on the line 8—8 of Fig. 9; Fig. 9 is a detail front elevation 45 of the machine showing the parts illustrated in Fig. 8; Fig. 10 is similar to Fig. 9 but shows the parts in a different position; and Figs. 11 and 12 are detail perspective views showing different operative positions of the 50 parts.

The drawings illustrate a form of grain shucker applied to a harvesting machine as an attachment. The so-called bull wheel of the harvesting machine is indicated in the 55 drawings at 25. A pair of longitudinal frame members of the harvesting machine

are shown at 26 and 27. The inclined platform upon which the grain is tied into bundles is shown at 28. A needle shaft, constructed in the usual manner to make one oscillation during the tying of each bundle of grain, is shown at 29. A cam shaft 30, constructed to make one revolution during the tying of each bundle of grain, extends longitudinally over the platform 28. This cam shaft carries the usual ejector arms 31 for engaging and ejecting the completed bundles of grain.

In order that the grain shucker may be applied as an attachment to a harvesting machine of the form shown, a frame 48, comprising two horizontally disposed U-shaped bracket members 32 and 33, is preferably employed. When so constructed the U-shaped bracket members 32 and 33 each have their ends secured to the longitudinal frame members 26 and 27 of the harvesting machine, as at 34 and 35 (Fig. 2). The U-shaped bracket members 32, 33, are rigidly connected by means of a plurality of horizontally disposed channel bars, as 36, 37 and 38. Similarly a plurality of bracket arms 39, 40 and 41, are bolted to the under side of the platform 28 adjacent its outer edge, to extend outwardly and upwardly therefrom. A bracket 42, also secured to the under side of the platform 28 adjacent its outer edge, and a bracket 43 (Fig. 1) secured to the frame of the harvesting machine adjacent its front end, serve for supporting certain of the operative parts of the grain shocking attachment. Power for operating the several parts of the grain shocking attachment is derived from the continuously rotating parts of the harvesting machine, as the transverse shaft 44 and the longitudinal shaft 45.

A cradle 46 serves for collecting the bundles of grain and depositing them upon the ground in the form of a shock. As shown, this cradle is carried by an arm 47 which projects laterally outward from the frame 48. A carrying wheel 49 is rotatably mounted upon the outer end of the arm 47 and runs upon the ground at one side of the harvesting machine to assist in the support of the arm 47. The cradle 46 is preferably so constructed as to receive the bundles of grain with the butt ends of the grain turned in the direction of movement of the harvesting machine, and to be turned end for end and tilted backwardly to discharge its load.

upon the ground when a sufficient number of bundles for the formation of a shock have been depositing in it. The cradle is shown as having a frame comprising a plurality of curved transverse bars 50, 51, and 52, and a plurality of longitudinal bars, as 53 and 54. The two sides of the cradle are of like construction and but one is shown in the drawings.

- 10 The longitudinal bar 53 forms one of the side rails of the frame of the cradle. In order that the frame of the cradle may have the tapering form of a completed shock, the bar 53 is inclined with respect to the bar 54. 15 Wings, one of which is shown at 55, are provided at each side of the cradle 46 for compressing the contents of the cradle during its tilting to discharge its load upon the ground. The wing 55 comprises a crank 20 shaft 56 arranged parallel with and adjacent to the bar 53, and a plurality of radially extending prongs 57, 58, 59, the latter being movable over the contents of the cradle upon the turning of the shaft. 25 The crank shaft 56 is journaled adjacent its opposite ends in brackets 60 and 61. These brackets are mounted upon the transverse bars 51, 52, respectively, adjacent the corresponding side of the cradle frame. A 30 crank arm 62, mounted upon the crank shaft 56 adjacent one end, is provided for swinging the wing 55. This crank arm is connected by a link 63 with one of the arms of a bell crank lever 64. The bell crank lever 35 64 is pivotally mounted upon a bracket 65. This bracket is secured to an adjacent portion of the cradle frame, as the transverse bar 51. A spring 66, coiled about the crank shaft 56 and reacting between the adjacent 40 side bar 53 of the cradle frame and one of the prongs, as 58, serves for swinging the wing 55 in that direction to turn the prongs 57, 58, 59, away from the body of the cradle. A link 69, having one end joined to the bell 45 crank lever 64, serves for operatively connecting the wing 55 with a similar but oppositely movable wing (not shown) located at the other side of the cradle frame.

A V-shaped frame 67 is preferably provided for separating the bundles of grain adjacent their lower ends in order that the shock will have a wide base when deposited upon the ground. As shown, the V-shaped frame 67 takes the form of a bar bent to the 55 shape of the frame and having its opposite ends secured to the transverse bar 50 of the cradle frame at each side of the mid-length of the bar.

A base block 68 is preferably secured to 60 the under side of the cradle frame at the juncture of the intermediate transverse and longitudinal bars, as 51 and 54. This base block is preferably mounted for rotation in a horizontal plane, as in a bracket 69. To 65 permit the tilting of the cradle, the bracket

69 turns about the arm 47 in a vertical plane. The rotation of the base block 68 in a horizontal plane serves for turning the cradle 46 end for end. The base block 68 has a downwardly projecting stud 70 (Fig. 8) 70 upon its underside. This stud enters a socket 71, formed in the bracket 69. A pin 72, set transversely through the walls of the socket 71 and entering a circumferential groove in the stud 70, serves to hold the stud 75 in the socket. Preferably a ball bearing 73, of usual construction, is provided between the upper end of the bracket 69 and the under side of the body portion of the base block 68. The means for turning the 80 block 68 includes a series of downwardly facing beveled gear teeth 74 formed upon the block. A shaft 75, projecting horizontally outward from the frame 48, is journaled adjacent its outer end in the bracket 85 69 and carries a beveled pinion 77 which meshes with the beveled gear teeth 74 upon the block 68. For tilting the cradle 46 a second shaft 78 projects horizontally outward from the frame 48. A bracket 78', fixed 90 upon the arm 47 adjacent the rotatable bracket 69, provides a bearing for the other end of the shaft 78. A crank arm 79 having a cam slot 80 is mounted upon the outer end of the shaft 78. An arm 81, formed integral with the rotatable bracket 69, projects outwardly from the bracket, substantially parallel with the crank arm 79, and is provided with a stud 82 which runs in the cam slot 80. 100

Preferably provision is made for locking the cradle 46 against tilting when it is turned to the position illustrated in Fig. 1, wherein it serves to receive the bundles of grain. As shown, means for locking the 105 cradle against turning when it is being tilted to discharge its load upon the ground is also provided. A latch 83 serves for locking the cradle against tilting. A second latch 84 serves for locking the cradle against 110 turning. The latch 83 (Fig. 10) is pivoted at 85 upon a part of the rotatable bracket 69, and normally engages a laterally projecting shoulder 86 of the non-rotatable bracket 78'. A spring 87 reacts between the 115 higher end of the latch 83 and a stud 88 carried by the rotatable bracket 69 to yieldingly hold the latch in engagement with the shoulder. When the cradle 46 is turned end for end the latch 83 is released from the shoulder 86. For this purpose a crank arm 89 (Fig. 8) mounted upon and turning with the base block 68 comes into engagement with the latch as the turning movement of the cradle is completed. 120

The latch 84 is pivoted at 90 upon a stud 91 which is formed integral with and rises from the rotatable bracket 69. This latch is normally held in elevated position by means of a swinging post, shown at 92 (Fig. 130

9). For supporting the post 92, an arm 94 projects laterally from the non-rotatable bracket 78'. The post is pivoted to this arm at 93. A rod 95 projects from one side 5 of the latch 84 and normally rests upon the top of the post 92. A spring 96 normally holds the post 92 in position beneath the rod 95. This spring reacts between the lower end of the post 92 and a fixed part of the 10 non-rotatable bracket 78'.

When the cradle 46 is turned end for end the crank arm 89 serves to move the post 92 from beneath the rod 95. The latch 84 is thereby permitted to be drawn down by 15 its spring and to engage with the crank arm 89 to hold the base block 68 and cradle 46 against rotation. As shown, a pivoted stop 97 is carried by the post 92. This stop is normally held in the path of the crank arm 20 89 by a spring 98. This spring reacts between the forward end of the stop and a fixed part of the non-rotatable bracket 78', as the pivot 93 of the post 92. The crank arm 89 swings the post 92 by engaging the 25 stop 97. During the tilting of the cradle, the crank arm 89 is raised out of engagement with the stop 97 and the spring 86' returns the post 92 to position beneath the rod 95. As the cradle is returned to horizontal 30 position after being tilted, the rod 95 comes into engagement with the post 92. The latch 84 is thereby lifted out of engagement with the crank arm 89. This releases the cradle for horizontal rotation and 35 it is returned to the position shown in Fig. 1. As the stop 97 is in the path of the crank arm 89, when the cradle is returned after being tilted, it is deflected downwardly 40 against the effort of the spring 98 to permit the crank arm to assume its normal horizontal position.

A carrier, generally designated 100, is provided for transferring the bundles of grain from the bundle producing mechanism 45 to the cradle 46. As shown, this carrier comprises a plurality of endless chains 101, 102, 103. Each of these chains extends about sprocket wheels, as 104, and 105. These sprocket wheels are mounted upon 50 parallel shafts shown at 106 and 107. The shafts 106 and 107 are preferably carried by and journaled in the bracket arms 39, 40 and 41. They are so positioned upon these bracket arms as to support the carrier 100 55 for receiving the bundles of grain as they are ejected from the bundle producing mechanism by the ejector arms 31 and to deliver them over the adjacent side of the cradle 46. Each of the chains 101, 102 and 103 is 60 shown as being equipped with an outwardly projecting prong 108. These prongs serve to engage and elevate the bundles of grain during the movement of the chains.

The carrier 100 is intermittently driven 65 by rotating the shaft 106. To this end, each

of the sprocket wheels 104 is preferably fixed upon said shaft. Power for turning the shaft 106 is conveniently derived from the continuously rotating shaft 45 of the harvesting machine. An intermediate shaft 70 109 is provided for transmitting this power when the carrier is to be operated. This shaft is preferably journaled upon the bracket 42. A sprocket chain 110 turns over a sprocket wheel 111 on the shaft 109 and 75 over a sprocket wheel 112 on the shaft 106. A gear pinion 113, is also mounted on the shaft 109. This gear pinion is continuously engaged by a movable gear 114. This movable gear is shifted into and out of engagement with a gear 115 mounted on the shaft 45, thereby serving as a clutch for controlling the operation of the carrier. As shown, the intermediate gear 114 is mounted upon a bracket arm 118 which hangs from the 80 shaft 109 and moves upon such shaft as a center.

Preferably provision is made for shifting the movable gear 114 into engagement with the gear 115 whenever a bundle of grain 90 has been completed by the bundle producing mechanism and for returning such gear to its inoperative position to arrest the movement of the carrier when it has been operated through a certain distance. Normally 95 the movement of the carrier 100 will be arrested when the prongs 108 reach the position shown in Fig. 2, but at each movement of the carrier which immediately follows the operation of setting the cradle 46 in 100 motion to discharge its load upon the ground, the carrier will be arrested when the prongs 108 reach the position shown in Fig. 11. At such times the carrier will 105 serve to retain a bundle of grain until another bundle has been produced. The operation of the cradle to discharge its load upon the ground and to return it to receiving position may, therefore, occupy the time consumed in the production of two bundles of 110 grain, should this be required.

As shown, a shipper lever 116 serves for moving the gear 114 into and out of engagement with the gear 115. This shipper lever is pivotally mounted upon the bracket 42 115 as at 117 and is connected with the movable bracket 118, at 119. A lever 120 actuated by the needle shaft 29 of the harvesting machine, serves for depressing the shipper bar 116 to start the carrier 100. This lever is pivotally mounted upon the frame of the machine, as at 121, Fig. 6. It is slotted, as indicated at 122, to receive a wrist pin 123 of a crank arm 124 formed upon the needle shaft 29. The free end of the lever 120 extends over the shipper bar 116 in the manner most clearly shown in Figs. 7 and 11. A trip 125 carried by one of the chains, as 101, of the carrier 100, normally serves 125 for raising the shipper arm 116 to arrest 130

- the action of the carrier. A second trip 133, mounted on the chain 101, serves for engaging a jointed lever 132 to raise the shipper bar 116, when the carrier is to be brought to rest in the position shown in Fig. 11. A counting wheel 126 is provided for causing the jointed lever 132 to be moved into the path of the trip 133 at the proper time. This counting wheel is journaled in any convenient position as at the lower end of a bracket 127 Fig. 6, secured to the underside of the platform 28. As shown, the counting wheel takes the form of a ratchet wheel having teeth equal in number to the number of bundles desired to be deposited in the cradle 46 for the formation of a shock. In order that the counting wheel 126 may be turned through an angular distance equal to the spacing of its ratchet teeth for each bundle of grain produced, a pawl, 128 is provided. This pawl is shown as being pivotally attached to the lever 120. It is yieldingly held into engagement with the periphery of the counting wheel by means of a spring 129. This spring reacts between the pawl and the lever 120.
- The counting wheel 126 carries two cam arms indicated at 130 and 131 respectively. The cam arm 130 serves for swinging the jointed lever 132 into position to be engaged by the trip 133. The jointed lever 132 is mounted to swing in a horizontal plane, as by being pivotally attached adjacent to one end to the underside of the bracket 127. Its joint 134 permits of its outer end being moved vertically by the trip 133. A cam arm 135 mounted on the chain 101 of the carrier 100 serves for returning the jointed lever 132 to a position in which its outer end is out of the path of the trip 133. This operation is illustrated in Fig. 12 of the drawings. In order that the trips 125 and 133 will not serve to prevent the shipper bar 116 being depressed by the arm 120, these trips are so proportioned as to become disengaged from the parts which they respectively engage when the shipper bar has been raised a sufficient distance to arrest the operation of the carrier.
- 50 A shipper bar 136 is provided for starting the operation of the shock forming cradle 46. This shipper bar normally extends to a point adjacent the path of a trip 137 mounted on the chain 101 of the carrier 100.
- 55 As shown, the shipper bar 136 is pivotally supported beneath the platform 28 as at 138, Fig. 6. When the shock forming cradle is to be operated, the cam arm 131 of the counting wheel 126 moves the shipper bar 136 into the path of the trip 137. To this end the shipper bar is provided with a laterally projecting arm 139 which extends into the path of the cam arm 131, (Fig. 11). Preferably the two cam arms 130 and 131 are so positioned upon the counting wheel

126 as to be simultaneously operable upon the parts which they respectively engage.

The shipper bar 136 is shown as taking the form of a bell crank lever. One of the arms of this lever is slotted as indicated at 140, Fig. 7, to receive a stud 141, mounted upon the end of a clutch operating lever 142, (Figs. 3, 7). The clutch operating lever 142 is pivoted intermediate its ends, as at 143, upon one of the longitudinal bars 36 of the frame 48. The clutch controlled by the lever 142 operates between a sprocket wheel 144 and the continuously rotating shaft 44. The sprocket wheel 144 is mounted upon the shaft 44 and the shaft normally turns independent of the wheel. The hub of the wheel carries a laterally projecting spring depressed pawl 145. This pawl extends over a ratchet wheel 146 fixed upon the shaft 44. In the normal position of the clutch operating lever 142, the end of this lever extends beneath the pawl 145 and serves to hold it out of engagement with the ratchet wheel 146.

The pin and slot connection 140, 141 between the shipper bar 136 and the lever 142 permits of the shipper bar being raised into the path of the trip 137 without moving the lever. When the shipper bar 136 is raised by the trip 137, the lever 142 is so shifted as to remove its end from beneath the pawl 145 whereby the sprocket wheel 144 is caused to rotate with the shaft 44 by the engagement of the pawl with the ratchet wheel 146.

The sprocket wheel 144 is connected by a chain 147 with a sprocket wheel 148 mounted upon a counter shaft 149. The counter shaft 149 is carried by the frame 48 as by being journaled in brackets 150 and 151, Fig. 2, which depend from the longitudinal bars 36, 37, respectively, of the frame. Power for operating the shock forming cradle is derived from the counter shaft 149 and the parts are preferably so constructed that the counter shaft turns through one complete revolution during each operation of the cradle.

The sprocket wheel 148 has a laterally extending cam projection 152. The clutch operating lever 142 and the shipper bar 136 each have lugs which project into the path of this projection. These lugs are designated 153 and 154 respectively. During the rotation of the sprocket wheel 148 the lever 142 is restored to bring its end into the path of the pawl 145 by the engagement of the lug 153 with the cam projection 152. As the pawl 145 will not, at this time, be in position to be raised by the end of the lever 142, the sprocket wheel 148 will continue to rotate whereby the cam projection 152, after passing cam lug 153, engages the cam lug 154 and withdraws the shipper bar 136, from the path of the trip 137. The pawl 145 will have then traveled far enough to ride upon the end of the lever 142 to be raised thereby.

out of engagement with the ratchet 146. This brings the sprocket wheel 148 and counter shaft, 149, to rest.

The shaft, 75, is journaled adjacent its inner end in a part of the frame 48 as upon a bracket 158 which depends from the longitudinal rail 37, (Fig. 4). A universal joint 159 formed in the shaft 75 adjacent its inner end permits of those movements of the outer end of the shaft which are incident to the operation of the cradle. A sprocket wheel 160, mounted upon the inner end of the shaft, 75, is connected with a sprocket wheel 162, by a sprocket chain, 161. The sprocket wheel 162 is mounted between and is journaled upon depending brackets as 163 carried by the longitudinal rails, 36 and 37, of the frame 48.

A partial rotation of the sprocket wheel 162 in each direction serves for turning the cradle 46 end for end and for restoring it to its bundle receiving position. A pitman, 164, is connected with the sprocket wheel 162, for oscillating it. One end portion of the pitman 164 is bifurcated, its two arms 165 and 166 being extended above and below the counter shaft 149 adjacent a cam disk, 167, mounted on the shaft. A pair of pins, 168 and 169 project laterally from the cam disk, 167, for engaging the arms 165, 166 respectively of the pitman 164 to move it in opposite directions. One of the arms, as 165 of the pitman 164, is extended beyond the counter shaft 144, and is guided and supported in a bracket 170, carried by a transverse part, as 32, of the frame 48.

A pair of studs, 171 and 172, project laterally at the opposite side of the cam disk, 167, from the pins 168 and 169 for tilting and restoring the cradle 46. These studs engage the two arms, 173 and 174, respectively, of a bifurcated pitman, 175, to move the pitman back and forth. One of the arms, as 173, of the pitman 175, is extended through and guided and supported by the bracket 170. The pitman, 175, is connected to a rock arm 176. This rock arm is coaxially mounted at its higher end with the sprocket wheel 162. At its lower end it is connected by a link 177, with a crank arm, 178. This crank arm is mounted upon the inner end of the shaft 78. The shaft, 78, like the shaft, 75, is journaled adjacent its inner end in a bracket, as 179, which depends from the longitudinal rail 37, of the frame 48. The shaft, 78, is also provided with a universal joint 180 adjacent its inner end. A pair of springs, 181 and 182, oppositely coiled about the arm 47 adjacent the rotatable bracket, 69, and each reacting between the arm, 47, and the stud 88, formed upon the bracket 69, serve for cushioning the movement of the rotatable bracket 69 in each direction as the cradle 46, is tilted and restored. One of these springs also serves

for assisting the initial tilting movement of the cradle in each direction.

A cam, 184, mounted on the counter shaft, 149, serves for closing the lateral wings, as 55, of the cradle upon the contents of the cradle during the tilting. This cam reacts upon a cam roller 185, located at one end of a lever, 186, Fig. 4. The lever, 186, is pivotally mounted upon one of the longitudinal bars, as 38, of the frame 48. It is connected by a link 187 with one of the arms of a horizontally movable bell crank lever 188. The other arm of the bell crank lever 188 is connected by a link 190 with a rock arm 191. The bell crank lever 188 is pivotally mounted upon a bracket 189 secured to the longitudinal bar 38 of the frame 48 and projecting outwardly therefrom. The rock arm 191 is pivoted upon the rotatable bracket 69 and depends therefrom. This rock arm is connected by a pull cord 192 with the bell crank lever 64. Referring to Fig. 2 of the drawings, the pull cord 192 rotates about the rock arm 191 when the cradle 46 is turned end for end. It then extends beyond the rock arm 191 and serves to transmit a pulling movement from the link 190 to the bell crank lever 64. This serves to swing the prongs 57, 58 and 59 of the wing 55 inwardly upon the contents of the cradle. Outward movement of the prongs 57, 58, 59 and the restoration of the bell crank levers 64 and 188 to their original positions are effected by the spring 66 when the lever 186 is released by the cam 184.

Provision is preferably made for moving the cradle 46 backwardly with respect to the frame 48 when it deposits its load upon the ground. By this means the travel of the cradle over the ground is interrupted as it deposits its load. As shown, the arm 47 is mounted for longitudinal movement with respect to the frame 48. To this end the inner end of the arm 47 is secured to a block 193 and this block is slidingly mounted upon the longitudinal bar 38 of the frame 48. Antifriction rollers 194 carried by the block 193 run upon the upper side of the bar 38.

A cam disk 195 mounted on the counter shaft 149 serves for moving block 193 to interrupt the travel of the cradle 46 and returning it to its normal position with respect to the frame 48. As shown, the cam disk 195 is provided with a pair of laterally projecting studs 196 and 197. These studs 196 and 197 co-operate with the two arms 198 and 199 respectively, of a bifurcated pitman 200 to move the pitman back and forth. One of the arms, as 199 of the pitman, extends through and is guided and supported in a bracket 201 mounted upon the part 32 of the frame 48. The pitman 200 is operatively connected at 202, Fig. 3, with a lever 204. The lever 204 is pivotally mounted upon the upper part of the bracket 189. A link 205

connects the lever 204 with the block 193. A second link 206, connects the lever 204 with an arm 207 (Fig. 1) located adjacent the forward end of the harvesting machine. The arm 207 is pivotally supported at one end upon the bracket 43. It carries a stud 208 which normally extends into the path of a lever 209 to prevent rearward movement of the same. The lever 209 is pivotally mounted upon the frame of the harvesting machine, as at 210. It extends laterally outward therefrom and has its outer end connected by a link 211 with the outer end of the arm 47. When the lever 204 is operated to retract the block 193, the arm 207 is also retracted, whereby rearward movement of the lever 209 is permitted. By this means the forward travel of both the inner and outer ends of the arm 47 is interrupted. When the cradle 46 has been restored, a reverse movement of the lever 204 advances the block 193 and also swings the arm 207 forwardly. The stud 208 then bears outwardly upon the lever 209 to advance the outer end of the arm 47. Flexing of the shafts, 75 and 78 sufficient to accommodate the above described movement of the arm 47 is permitted by the universal joints 159 and 180.

In the normal operation of the parts the shipper bar 116 is released by the lever 120 before the carrier 100 will have been moved through a sufficient distance to bring either of the trips 125 or 133 into position to engage the shipper bar 116 and jointed lever 132 respectively. Should the production of bundles of grain be so rapid that the lever 120 will be depressed upon the shipper bar 116 a second time before the trip 125 reaches the shipper bar 116, or the trip 133 reaches the jointed lever 132, provision is made for causing the trips to clear these parts. To this end the lever 120 is so proportioned as to depress the shipper bar 116 below the path of the trip 125. By this means the jointed lever 132 is also depressed below the path of the trip 133. A coil spring 213 reacting between the shipper bar 116 and the underside of the platform 28 serves to raise the shipper bar 116 into the path of the trip 125 when the shipper bar is released by the lever 120. Similarly a leaf spring 212 reacting between the parts of the jointed lever 132 serves for returning the outer end portion of this lever into the path of the trip 133.

The shipper bars 116 and 136 are preferably located upon opposite sides of the path of the prong 108 of the chain 101. The trips 125 and 133 and the cam arm 136 are accordingly located upon one side of the chain 101. The trip 137 is located upon the other side of the chain 101.

I claim as my invention—

1. In a grain shucker in combination, a

tilting cradle rotatable when horizontally disposed upon a vertical axis means acting successively to turn the cradle end for end upon the said vertical axis and to tilt the cradle, a latch holding the cradle against 70 tilting during the turning of the cradle and a latch holding the cradle against turning during the tilting of the cradle.

2. In combination, bundle tying mechanism, means in which the bundles are collected acting to form a shock when a number of bundles have been collected therein, a conveyer receiving bundles from the bundle tying means and delivering them to the bundle collecting and shock forming means, 80 a counting wheel actuated by the bundle tying mechanism and controlling the operation of the bundle collecting and shock forming means, a pair of trips on the conveyer, a pair of shipper levers controlling 85 the operation of the conveyer and one thereof extending into the path of one of the said trips and means actuated by the counter wheel at each complete revolution of the same for moving the other shipper lever 90 into the path of the other trip.

3. In combination, bundle tying mechanism, shock forming mechanism, a carrier receiving bundles from the bundle tying mechanism and delivering them to the shock 95 forming mechanism, a counting wheel turned by the bundle tying mechanism, a shipper lever controlling the operation of the carrier, a trip on the carrier, and means operated by the counting wheel at each complete revolution of the same for moving the shipper lever 100 into the path of the trip.

4. In combination, bundle tying mechanism, shock forming mechanism, a traveling conveyer receiving the bundles from the bundle tying mechanism and delivering them to the shock forming mechanism, a counting wheel turned by the bundle tying mechanism, a clutch controlling the operation of the shock forming mechanism, a movable shipper lever connected to the clutch, a trip carried by the traveling conveyer and means operated by the counting wheel at each revolution of the same for moving the shipper lever into the path of 110 the trip.

5. In combination, bundle tying mechanism, shock forming mechanism, a traveling conveyer receiving bundles from the bundle tying mechanism and delivering them to the shock forming mechanism, a counting wheel turned by the bundle tying mechanism, a clutch controlling the operation of the shock forming mechanism, a second clutch controlling the operation of the traveling conveyer, a movable shipper lever connected to each of the said clutches, a pair of trips carried by the traveling conveyer and means actuated by the counting wheel at each complete revolution of the same for moving 125 130 135

each of the shipper levers into the path of one of the trips.

6. In combination, bundle tying mechanism, shock forming mechanism, a traveling conveyer receiving bundles from the bundle tying mechanism and delivering them to the shock forming mechanism, a counting wheel turned by the bundle tying mechanism, a clutch controlling the operation of the shock forming mechanism, a second clutch controlling the operation of the traveling conveyer, a shipper lever connected to each of the said clutches, two trips carried by the traveling conveyer and located in different positions thereon, means actuated by the bundle tying mechanism and operable upon the completion of each bundle of grain produced thereby to move the shipper lever which is connected to the clutch for controlling the conveyer into the path of one of said trips, means actuated by the counting wheel at each complete revolution of the same for causing said last mentioned shipper lever to be moved by the other of said trips, a third trip carried by the traveling conveyer and means actuated by the counting wheel at each complete revolution of the same for moving the shipper lever which is connected to the said clutch for controlling the operation of the shock forming mechanism into the path of the last mentioned trip.

7. In a harvesting machine, in combination, a traveling frame, a trough shaped shock former carried by the frame and normally occupying a horizontal bundle collecting position, means for turning the shock former to an upright position for the discharge of its load through its top by the forward travel of the frame with the contents of the shock former engaged with the ground and means for moving the shock former backwardly with respect to the frame to temporarily compensate for the forward travel of the frame when the load of the shock former is first engaged with the ground and before its discharge from the shock former by the said forward travel of the frame.

8. In combination with a harvesting machine, an arm projecting laterally outward at one side of the machine, a cradle carried by said arm and normally occupying a horizontal position above the arm, a conveyer receiving bundles of grain from the harvesting machine and operating to deliver them to the cradle and means automatically controlled by the said delivery of bundles to the cradle acting successively for turning the cradle end for end when a predetermined number of bundles of grain have been delivered to the cradle and for tilting the cradle about the arm to an upright position for the discharge of its load through its top by the forward travel of the harvesting machine

when the contents of the cradle is engaged with the ground.

9. In a grain shucker, in combination, a traveling frame, a tilting shock forming cradle carried by the frame and rotatable when horizontally disposed upon a vertical axis, means acting successively to turn the cradle end for end upon the said vertical axis and to tilt the cradle to an upright position for the discharge of its load through its top by the forward travel of the frame when the contents of the cradle is engaged with the ground, a latch holding the cradle against tilting during the turning of the cradle and a latch holding the cradle against turning during the tilting of the cradle.

10. In a harvesting machine, in combination, a traveling frame, a trough shaped shock former carried by the frame and normally occupying a horizontal bundle collecting position, means acting successively to turn the shock former end for end in a horizontal plane and to turn the shock former to an upright position for the discharge of its load through its top by the forward travel of the frame with the contents of the shock former engaged with the ground, means acting to laterally compress the contents of the shock former during the turning of the same to an upright position and means for moving the shock former backwardly with respect to the frame to temporarily compensate for the forward travel of the frame when the load of the shock former is first engaged with the ground and before its discharge from the shock former by the said forward travel of the frame.

11. In a harvesting machine, in combination, a traveling frame, a trough shaped shock former carried by the frame and normally occupying a horizontal bundle collecting position, means acting successively to turn the shock former end for end in a horizontal plane and to turn the shock former to an upright position for the discharge of its load through its top by the forward travel of the frame with the contents of the shock former engaged with the ground, and means for moving the shock former backwardly with respect to the frame to temporarily compensate for the forward travel of the frame when the load of the shock former is first engaged with the ground and before its discharge from the shock former by the said forward travel of the frame.

12. In a grain shucker, in combination, a traveling frame, a tilting shock forming cradle carried by the frame and rotatable when horizontally disposed upon a vertical axis, means acting successively to turn the cradle end for end upon the said vertical axis and to tilt the cradle to an upright position for the discharge of its load through its top by the forward travel of the frame when the contents of the cradle is engaged

with the ground and a latch acting to hold the cradle against tilting during the said turning of the same.

13. In a grain shocker, in combination, a traveling frame, a tilting shock forming cradle carried by the frame and rotatable when horizontally disposed upon a vertical axis, means acting successively to turn the cradle end for end upon the said vertical axis and to tilt the cradle to an upright position for the discharge of its load through its top by the forward travel of the frame when the contents of the cradle is engaged with the ground and a latch acting to hold the cradle against turning during the said tilting of the same.

14. In combination with a harvesting machine, a trough shaped shock former carried by the harvesting machine and normally occupying a horizontal position for collecting bundles of grain formed by the machine, automatic means acting when a predetermined number of bundles of grain have been so collected to turn the shock former to an upright position for the discharge of its load through its top by the forward travel of the harvesting machine with the contents of the shock former engaged with the ground, and means for moving the shock former backwardly with respect to the harvesting machine to temporarily compensate for the forward travel of the machine when the load of the shock former is first engaged with the ground and before its discharge from the shock former by the said forward travel of the harvesting machine.

15. In combination with a harvesting machine, a trough shaped shock former carried by the machine and normally occupying a horizontal position for collecting bundles of grain formed by the machine, automatic means acting successively when a predetermined number of bundles of grain have been so collected to turn the shock former end for end and to tilt the shock former to an upright position for the discharge of its load through its top by the forward travel of the harvesting machine with the contents of the shock former engaged with the ground, and means for moving the shock former backwardly with respect to the harvesting machine to temporarily compensate for the forward travel of the machine when the load of the shock former is first engaged with the ground and before its discharge from the shock former by the said forward travel of the harvesting machine.

16. In a harvesting machine, in combination, a traveling frame, a trough shaped shock former carried by the frame and nor-

mally occupying a horizontal bundle collecting position, means acting to laterally compress the contents of the shock former, means for turning the shock former to an upright position for the discharge of its load through its top by the forward travel of the frame with the contents of the shock former engaged with the ground, and means for moving the shock former backwardly with respect to the frame to temporarily compensate for the forward travel of the frame when the shock former has been turned to the said upright position and the said compressing means has been released.

17. In a harvesting machine, in combination, a traveling frame, a trough shaped shock former carried by the frame and normally occupying a horizontal bundle collecting position, means acting to laterally compress the contents of the shock former, means acting successively to turn the shock former end for end and to tilt the shock former to an upright position for the discharge of its load through its top by the forward travel of the frame with the contents of the shock former engaged with the ground, and means for moving the shock former backwardly with respect to the frame to temporarily compensate for the forward travel of the frame when the shock former has been tilted to the said upright position and the said compressing means has been released.

18. In a shock former, in combination, a traveling frame, an arm projecting laterally outward from one side of the frame the inner end of the arm being connected to the frame for longitudinal movement thereon, a carrying wheel supporting the outer end of the arm, a tilting cradle mounted on the arm, and means acting simultaneously on both the inner and outer ends of the arm for moving the arm relatively to the frame parallel to the direction of travel of the frame.

19. In a shock former, in combination, a traveling frame, an arm projecting laterally outward from one side of the frame, a tilting cradle mounted on the arm, said cradle normally occupying a substantially horizontal position with its axis parallel to the direction of travel of the frame and having an open end, means for tilting the cradle about the arm to an upright position and power-actuated means acting on the outer end of the arm to move the cradle longitudinally with respect to the said frame when the cradle reaches said upright position.
